DE VERE W. TERPENNEY

FIRE STARTER

Filed Feb. 6, 1925

WITNESS: J. J. L. Wright

INVENTOR
BY *Victor J. Evans*

ATTORNEY

UNITED STATES PATENT OFFICE.

DE VERE W. TERPENEY, OF DETROIT, MICHIGAN.

FIRE STARTER.

Application filed February 6, 1925. Serial No. 7,351.

To all whom it may concern:

Be it known that I, DE VERE W. TERPENEY, a citizen of the United States, residing at Detroit, in the county of Wayne 5 and State of Michigan, have invented new and useful Improvements in Fire Starters, of which the following is a specification.

This invention relates to improvements in means for igniting coal or other fuel in 10 heating furnaces without the use of kindling, charcoal or kerosene, consisting in subjecting the coal or other fuel to an intense gas flame from a burner pipe whereby ignition is accomplished.

15 Another object of the invention is the provision of a tapered forward end portion which includes longitudinally extending radially disposed apertured ribs which owing to their peculiar configuration will allow 20 a greater volume or spread of flame when inserted in the fuel or the like so that the fire will be more quickly started.

25 A further object of the invention is the provision of a novel form of tool which owing to its simplicity of construction and novel arrangement of parts, may be easily and readily attached to a hot water heater pipe which is arranged adjacent the heating furnace and readily and easily attached thereto 30 whereby the fire starter may be positioned adjacent the draft opening in the front of the furnace in order that it may be readily and easily inserted therein.

35 With the above and other objects in view, the invention further includes the following novel features and details of construction, to be hereinafter more fully described, illustrated in the accompanying drawing and pointed out in the appended claim.

40 In the drawing:

Figure 1 is an elevation of the invention with the igniting means attached therewith.

Figure 2 is a vertical sectional view of the starter per se.

45 Figure 3 is a transverse section taken on line 3—3 of Figure 1.

Figure 4 is a similar view taken on line 4—4 of Figure 2.

Referring to the drawing in detail, where- 50 in like characters of reference denote cor- responding parts, the reference character 10 indicates a burner pipe which tapers toward its forward end portion and includes thereon a pointed end 11 and a plurality of longi- tudinally extending radially disposed aper-

tured ribs 12 arranged adjacent the pointed end 11 thereof. The opposite end of the pipe 10 is cross sectioned concaved as at 13 and includes thereon a coiled wire which acts as a heat insulating handle for the tool. 55 The rear end portion of the pipe 10 is pointed as at 15 and includes a plurality of elongated slots around the outer sides thereof and which slots are adapted to selectively register with correspondingly shaped slots 60 arranged in a cap member 16 including an inwardly extending annular flanged portion 17 which engages over the enlarged portion of the rear end portion 15 of the pipe 10 whereby the cap 16 may be held against ac- 65 cidental displacement on the rear end of the pipe 10 whereby the slots 18 therein may be brought into selective registration with cor- 70 responding slots arranged in the rear end of the pipe 10 whereby proper air inlet is as- 75 sured for the mixture of a gas therein. In order to provide gas inlet means for the pipe 10 I provide a relatively short pipe 19 which is threadedly secured as at 20 within the rear end 15 of the pipe 10 and which has se- 80 cured to the opposite end thereof a flexible tube 21 having a pet cock 22 connected to the opposite end thereof and which in turn includes a screw cap 23 whereby the tool may be connected or associated with a gas 85 pipe 24 through the instrumentality of the T-shaped pipe 25 which has its upper end portion threadedly secured within the screw cap 23.

It will thus be seen that upon turning on 90 of the gas to the pet cock 22 that the gas will enter through the flexible tube 21, the pipe 19, into the rear end 15 of the pipe 10 and upon turning or rotating the cap 16 95 upon the rear end 15 thereof it will be seen that a proper air mixture may be determined as indicated by the color of the blaze emitted from the forward end portion of the pipe 10 which would be preferably blue in order to facilitate heating and owing to the pointed 100 portion 11 upon the forward end portion of the pipe 10, it will be clearly apparent that the tool may be easily and readily inserted within a draft or other opening provided in the furnace whereby the said tool may be 105 inserted within the fire bed of the furnace and left in its position in order that the fire may be started without the use of kindling, charcoal, kerosene and the like, whereby a person may form a bed of coal within his 110

furnace and not smoke up the adjoining neighborhood with the smoke of trash, wood and the like generally used in starting fires.

The invention is susceptible of various changes in its form, proportions and minor details of construction and the right is herein reserved to make such changes as properly fall within the scope of the appended claim.

Having thus described my invention what is claimed is:

A fire starter of the character described comprising a forwardly tapered pipe having a relatively sharp forward end portion, a plurality of longitudinally extending radially disposed apertured ribs provided adjacent the forward end portion of the pipe, a constricted portion provided adjacent the rear end of the pipe, a coil of wire surround-

ing said constricted portion forming a handle, the rear end of the pipe being substantially pointed and including a plurality of elongated air inlet openings therein, a cap member received on this end and including an inwardly extending annular flange portion which extends over the enlarged inner portion of the rear end and including a plurality of correspondingly shaped registering air inlet openings therein, a relatively short pipe extending rearwardly from the rear end of the pipe, and fuel inlet means connected to this pipe whereby the mixer of the fuel emitted from the forward end portion of the burner pipe may be determined.

In testimony whereof I affix my signature.

DE VERE W. TERPENEY.
